[57] CLAIM

The ornamental design for a universal air chamber
mounting bracket, substantially as shown and described.

DESCRIPTION

FIG. 1 is a front view of a universal air chamber mount-
ing bracket showing my new design;

FIG. 2 is a top plan view of the universal air chamber
mounting bracket of FIG. 1;

FIG. 3 is a bottom plan view of the universal air cham-
ber mounting bracket of FIG. 1;

FIG. 4 is a right end view of the universal air chamber
mounting bracket of FIG. 1;

FIG. 5 is a left side view of the universal air chamber
mounting bracket of FIG. 1; and

FIG. 6 is a rear view of the universal air chamber
mounting bracket of FIG. 1.

FIG. 2FIG. 5FIG. 1FIG. 4FIG. 3FIG. 6
